VIBRATION ARRESTER FOR TUBE FRAMES

William W. Robertson, Northboro, Mass., assignor to Crompton & Knowles Loom Works, Worcester, Mass., a corporation of Massachusetts

Application April 15, 1936, Serial No. 74,527

9 Claims. (Cl. 139—9)

This invention relates to improvements in Axminster looms and it is the general object of the invention to prevent vibration of the tube frames as they are presented to the fabric and during the rolling-in operation which places tuft yarns between the binder warps.

Axminster looms operate with chains carrying a series of tube frames which are moved one at a time to tuft forming position. It is customary to employ a transfer arm at each side of the loom so arranged as to unclutch the tube frames from the chains and move them down toward the cloth. In wide looms the down motion of the tube frame is likely to be accompanied by an objectionable vibration of the tube frame, and this may also occur even when a carrier is provided to prevent sagging of the tube frame under the action of gravity. During the rolling-in operation the free color tuft yarns extending from the yarn tubes pass under and up behind a shot of filling laid by a weft needle. If the tube frame should vibrate upwardly a sufficient amount the color yarns are drawn under the pick of filling so that the rear part of the tuft is low. It is an important object of my present invention to impose a light restraining force on the tube frame at some point intermediate its ends to arrest the vibration and thereby insure the formation of full height tufts.

In my prior Patent No. 1,604,318 I have illustrated a tube frame carrier extending across the loom and so constructed as to support the tube frame throughout its length. When my present invention is applied to a loom having such a carrier the restraining force is applied preferably to the carrier and through the latter indirectly to the tube frame.

In carrying my invention into effect I find it convenient to employ a thin leaf spring sufficiently stiff to arrest vibrations but yielding enough to permit the rolling-in operations of the tube frame, or the carrier if the loom be provided with the latter. The leaf spring may be mounted on a support located approximately at the center of the loom and adjustable with respect to the path traversed by the tube frame during tuft forming operations to vary the pressure of the restraining force.

With these and other objects in view which will appear as the description proceeds, my invention resides in the combination and arrangement of parts hereinafter described and set forth.

In the accompanying drawings, wherein I have shown two forms of the invention,

Fig. 1 is a vertical section taken transversely through a loom and having the preferred form of my invention applied thereto, the tube frame about to become active being shown ready to leave the transporting chain, 5

Fig. 2 is a view similar to Fig. 1 but with the active tube frame in the process of forming the tuft,

Fig. 3 is a front elevation looking in the direction of arrow 3, Fig. 1 and illustrating the method 10 of supporting the vibration arrester,

Fig. 4 is a vertical detailed plan taken in the direction of arrow 4, Fig. 1, and

Fig. 5 is a view similar to a portion of Fig. 2 but showing a modified form of my invention 15 wherein a carrier bar supports the tube frame and is in engagement with the vibration arrester.

Referring to the drawings, I have shown a transporting shaft 10 with a sprocket 11 to advance a transporting chain 12 carrying a series 20 of tube frames 13. The shaft 10 may be mounted on the loom frame a portion of which is designated at 14 and may be driven by mechanism not shown but well understood. Each tube frame includes a bar 15 from which project a series 25 of relatively small narrow yarn tubes 16, and each tube frame carries a spool 17 to provide the tuft yarns 18 which extend through the tubes 16. A transverse shaft 20 has projecting forwardly therefrom at each end a carrier arm 30 21 on which is pivoted a clutch lever 22. The forward end of each lever is provided with a clutch 23 movable about a pivot 24 on the arm by forces transmitted through an operating rod 25.

During loom operation the sprocket 11 advances the tube frames to transfer position one at a time and the transfer arms 22 act to release the tube frame in lowest position from the chain. Thereafter the transfer shaft 20 rocks in a left 40 hand direction viewed in Fig. 1 to lower the tube frame, causing the tuft tubes 16 to enter between the warp binders W which extend from the rear of the loom forwardly to define a shed. When the tube frame is in low position it rolls from the dotted to the full line position shown in Fig. 2, after which the tube frame is caused to straighten to a substantially vertical position to be raised for the purpose of drawing the tuft yarn properly into position between the binders W.

The matter thus far described operates in the usual manner and of itself forms no part of my present invention. It is a matter of observation, however, that on wide looms during the descent 55

of the tube frame from the position of Fig. 1 to the positions indicated in Fig. 2 there may arise undesirable vibrations of the tube frame which as already stated interfere with the correct placing of the tuft yarns 18.

In carrying the preferred form of my present invention into effect I provide a support bracket 30 having a hub 31 which surrounds but is loose with respect to the transfer shaft 20. The support extends forwardly and is positioned vertically by a link 32 pivoted thereto and projecting upwardly through an angle brace 33 secured to the loom arch 34. Nuts 35 afford a vertical adjustment of the support 30 with respect to the arch so that the support may assume several vertical positions.

As set forth herein the support may have an upturned end 40 to the forward face of which is secured a strap 41 by means of bolt 42 and this strap extends downwardly and forwardly, terminating somewhat behind the path traversed by the tube frame as the latter moves from the transporting chain toward cloth forming position. A relatively light leaf spring 45, shaped and positioned as indicated in Fig. 1, is secured to the strap as at 46. The spring 45 projects into the path of the descending tube frame but does not engage the latter until it is near the cloth being woven. When the tube frame is low the leaf spring will exert a light force thereon tending to arrest vibration, with the result that the tubes 16 and tuft yarns 18 projecting therefrom are presented correctly between the warp binders W and the resultant tufts are of the proper height.

The modified form of my invention may be applied to looms of extra width wherein the tube frame may be carried from the chain to cloth forming position by means of a carrier bar 50 formed preferably of two sheet metal bent sections 51 and 52 extending across the width of the loom and supporting a tube frame throughout its length. When such a carrier is employed it will be engaged by the spring 45 to have its vibration arrested. The carrier and its relation to the tube frame may be the same as that set forth in my prior Patent No. 1,604,318 and the spring 45 will be so located as to project into the path of the carrier when the latter approaches the cloth. In either form of the invention the spring 45 is effective to prevent vibration of the tube frame by exerting a light yielding force either on the tube frame directly or on the carrier therefor at a point intermediate the ends of the tube frame.

In order that my invention may be used conveniently either with or without the carrier I provide the upper end of the spring with a slot 47 through which a bolt 46 passes. I loosen the latter and slide the spring back and forth on the strap 41 and correctly locate the spring with respect to the paths of either the tube frame or the carrier.

From the foregoing it will be seen that I have provided simple means for imposing a yielding resisting force to a tube frame moving toward cloth forming position for the purpose of arresting vibration thereof to the end that the tufts may be of the proper height and the yarn tubes register with the binders. It will also be seen that manipulation of the link 32 affords means for adjusting the position of the spring 45 vertically, while variation in the setting of said spring longitudinally of the strap 41 through adjustment of the bolt 46 permits the device to be used either for direct engagement with the tube frame, or 75 with the carrier.

Having thus described my invention it will be seen that changes and modifications may be made therein by those skilled in the art without departing from the spirit and scope of the invention and I do not wish to be limited to the details herein disclosed, but what I claim is:

1. In an Axminster loom, a transporting chain, a series of yarn tubes carried by the chain and from which project tuft yarns, carrier means to convey the yarn tubes and yarns from the transporting chain to cloth forming position along a given path, and yielding stationary means located intermediate the ends of the tube frame and projecting into the path of the carrier means to engage the latter and exert a yielding pressure thereon to arrest vibration of said carrier means. 15

2. In an Axminster loom, a series of yarn tubes from which project tuft yarns, carrier means to convey the yarn tubes and yarns to cloth forming position, a fixed support located intermediate the ends of the loom, and a stationary yielding element mounted on the support and projecting into the path of movement of the carrier means as the latter moves toward cloth forming position to engage said carrier means and arrest vibration 25 thereof.

3. In an Axminster loom, a set of yarn tubes, a carrier therefor having rolling-in movements during tuft forming operations of the loom, and stationary yielding means normally projecting 30 into the path of movements of the carrier and having friction and sliding engagement with the carrier during its rolling-in movements to arrest vibration thereof.

4. In an Axminster loom, a set of yarn tubes, a carrier therefor having rolling-in movements during the tuft forming operation of the loom, and stationary yielding means along which the carrier slides during the rolling-in movements to exert a vibration arresting force on said carrier. 40

5. In an Axminster loom, a set of yarn tubes, a carrier to support and convey the yarn tubes toward the cloth being woven, and normally stationary yielding means extending into and along the path of the carrier to engage and impose a 45 vibration arresting force on said carrier as the same moves.

6. In an Axminster loom having a transporting chain, a tube frame, transfer means to convey the tube frame from the chain to cloth forming 50 position, and normally fixed means to impose a yielding force on the tube frame at a point intermediate the ends thereof to arrest vibration of said tube frame.

7. In an Axminster loom having a transporting chain, a tube frame, transfer means to convey the tube frame from the chain to cloth forming position, and a fixed spring element extending along and into the path of travel of the tube frame to impose a yielding force on the tube frame to arrest vibration thereof. 55

8. In an Axminster loom having a transporting chain, a tube frame, a shaft, transfer means movable about the shaft to convey the tube frame from the chain to cloth forming position, a support mounted on the shaft and located intermediate the ends of the tube frame means to give the support a plurality of different fixed positions about the shaft, and a yielding element carried by the support and projecting into and along the path of movement of the tube frame as the latter moves from the transporting chain to cloth forming position to exert a force on the tube frame tending to arrest vibration thereof. 65

9. In an Axminster loom having a transporting 75

chain, a tube frame, a shaft, transfer means movable about the shaft to convey the tube frame from the chain to cloth forming position, a support mounted on the shaft and located at a point intermediate the ends of the loom, a spring carried by the support and projecting into the path of the tube frame as the latter moves from the

transporting chain to cloth forming position to arrest vibration of the tube frame, and means to hold the support and spring in any one of a plurality of fixed positions about the shaft to vary the position of said spring along the path of the tube frame. 5

WILLIAM W. ROBERTSON.
